UNITED STATES PATENT OFFICE.

ROBERT JAMES ELLIOTT, OF SANTA CRUZ, CALIFORNIA.

FEED-REGULATOR FOR LUBRICATORS.

SPECIFICATION forming part of Letters Patent No. 789,268, dated May 9, 1905.

Application filed January 11, 1904. Serial No. 188,548.

To all whom it may concern:

Be it known that I, ROBERT JAMES ELLIOTT, a citizen of the United States, residing at Santa Cruz, in the county of Santa Cruz and State 5 of California, have invented a new and useful Feed-Regulator for Lubricators, of which the following is a specification.

My invention relates to feed-regulators for lubricators, being designed especially for application to the class of devices known as "sight-feed" lubricators and having a plurality of feed-tubes, and has for its objects to produce a simple inexpensive device of this character which may be readily applied and one by which the amount of lubricant fed to the tubes may in practice be accurately regulated.

To these ends the invention comprises the novel features of construction and combination of parts more fully hereinafter described.

In the accompanying drawings, Figure 1 is a perspective view showing my improved regulator applied. Figs. 2 and 3 are detail views of the regulator.

Referring to the drawings, 1 designates the lubricator, having a condenser 2 and an oil-reservoir 3, there being attached and communicating with the latter a pair of feed-tubes 4, the feed-stems 5 of which are provided upon 25 their lower ends with operating-handles 6. These parts, which are foreign to my invention, may be of the usual or any preferred construction and operation, the ordinary practice being to connect the condenser 2 and reservoir 3 with a steam duct or main, from 30 which steam passes through said parts and feed-tubes, carrying the oil in quantities regulated by the latter back into the steam-main and thence delivering it, with the steam, to the 35 parts to be lubricated.

In accordance with my invention I affix in any suitable manner upon the stems 5 for rotation therewith graduated dials 7, preferably in the form of circular sheet-metal disks, and 45 provide above the graduated face of each dial a fixed non-rotary pointer or indicator 8, which serves, in conjunction with the dial, to determine the proper adjustment of the feed-stems 5 for regulating the flow of oil through the

feed-tubes. The pointers or indicators 8 are 50 preferably formed at the opposite ends of an indicator-plate 9, removably mounted beneath the lower end of the lubricator, and which, as shown in Fig. 2, preferably consists of a sheet-metal plate of substantially elliptical form 55 having a central opening 10, through which the usual drain-valve 11, provided beneath the reservoir 3, may in practice extend, and with end openings 12, adapted to receive the feed-stems 5.

In practice the plate 9 is first placed in position and the dials 7 fixed upon the stems beneath the plate, thereby retaining the latter in position, it being understood, of course, that owing to the engagement of the plate at 65 opposite ends with the stems horizontal movement of the plate will be prevented, and consequently the pointers 8 will be maintained fixed relative to the dials 7. It is also apparent that in practice by turning the stems 5 70 until certain graduations on the dials are brought opposite the pointers the flow of lubricant may be positively and accurately regulated. In order to prevent any shifting or turning of the stems when the same have been 75 adjusted, there is a coiled spring 12 mounted on each stem that bears at its upper end against the packing-nut 13 of each feed-tube and at its lower end against the terminal portions of the pointer. By this simple arrangement 80 it will be seen that any under or over feeding, more particularly the latter, due to the vibrations of the machinery to which the lubricator is attached, are obviated in a ready and practical manner.

From the foregoing it will be seen that I produce a simple inexpensive device which may be readily applied and will in practice efficiently perform its functions. In attaining these ends it is to be understood that I do 90 not limit myself to the precise details herein disclosed, as minor changes may be made without departing from the spirit of the invention.

Having thus described my invention, what 95 I claim is—

The combination with a lubricator comprising an oil-reservoir provided with a drain-

valve, a plurality of feed-tubes communicating with the reservoir, and feed-stems for the respective tubes, of dials carried by the feed-stems, a pointer having its terminals provided with orifices through which the feed-stems are passed and with a central orifice to engage the drain-valve to hold the pointer in position, and springs interposed between the packing-nuts of the feed-tubes and the termi-

nals of the pointer to hold the feed-stems in their adjusted positions.

In testimony that I claim the foregoing as my own I have hereto affixed my signature in the presence of two witnesses.

ROBERT JAMES ELLIOTT.
